UNITED STATES PATENT OFFICE.

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR CONVERTING HYDROCARBON OIL.

Application filed June 25, 1923. Serial No. 647,430.

This invention relates to improvements in a process and apparatus for converting hydrocarbon oil, and refers more particularly to a continuous process for the destructive distillation of oils to convert relatively high boiling point oils to oils of a low boiling point having the characteristics of gasoline.

The single figure is a diagrammatic side elevational view of the apparatus with parts broken away and parts in section.

In the drawing is shown a heating coil 1 mounted in a furnace 2, an expansion chamber 3 having an inner secondary container or receptacle 4, a dephlegmator 5, condenser 6 and a receiving tank 7. The oil to be treated is introduced from any convenient extraneous source through the line 8 and is charged by means of the pump 9, directly to the heating coils through the line 12 controlled by a valve 13, or it may be desirable to divert part of the charging stock to the dephlegmator through the line 10 regulated by the valve 11 and direct the remaining portion to the heating coil. If circulated through the dephlegmator and there utilized as a refluxing medium, the oil and what condensate it may collect, flows down through the dephlegmator leg 14 and may be drawn off through the line 15 controlled by a valve 16 through which it is directed to the expansion chamber 3 where it is brought in contact with the heated oil coming from the heating coil. If charged direct to the heating coil, the oil is raised to a cracking or conversion temperature in the heating coil 1 and passes thence through the transfer line 17 into the inner chamber 4 of the expansion chamber 3 where it is discharged and collects in a substantial body. The oil on filling up the container, overflows into the outer expansion chamber, vaporization taking place substantially from the time it is discharged in the inner container until the unvaporized liquid residual products are drawn off from the outer chamber through the line 18 regulated by a valve 19. The vapors evolved, rise to the top of the chamber, passing off through a vapor line 20 in which is interposed a valve 21, passing through the refluxing or fractionating column where they are subjected to the fractionating action of the tower into which may be introduced portions of the charging stock as a cooling medium, as explained. The uncondensed vapors pass off from the top of the tower through the vapor line 22 in which is

interposed a valve 23, and are subjected to a final condensing action in the condensing coil 6 after which the liquid distillate is discharged through the line 24 controlled by a valve 25 into the receiving tank 7.

The receiving tank is equipped with a pressure relief valve 26, pressure gauge 27, liquid level gauge 28 and a liquid drawoff line 29 controlled by a valve 30. By controlling the valves 30 and 26 on the receiver, the pressure in the system may be regulated to maintain desirable conditions for conversion. The reflux condensate separated out in the tower is returned and introduced to the outer shell of expansion chamber 3 wherein it is mixed with the heated oil overflowing from the inner container 4 and simultaneously therewith is in radiating contact with the oil contained in the inner container which serves to transmit to this returned product sufficient heat to promote further conversion and cracking.

The circulation of this relatively refractory condensate to the outer container has also the advantage of retarding the evolution of the vapors to an extent that the conversion or cracking proceeds at a slower rate, giving time for further complete digestion of the liquid body.

The time factor is of importance as it has been found that by maintaining the oil body at a high temperature for a considerable period of time and retarding to a limited extent the too rapid evolution of vapors, a more uniform and satisfactory distillate is obtained in the receiver, both in so far as its boiling point range is concerned and also with regard to other important characteristics which are factors in its marketability. At 31 is shown a drawoff line communicating with the inner container, by means of which any residual products tending to collect in the inner container may be withdrawn either continuously or intermittently.

This line 31 is controlled by suitable valve 32. The chamber 3 is shown mounted in a portion of the furnace, or in an insulated compartment adjoining the furnace whereby the space around the greater part of the chamber may be heated by means of the hot flue gases. This permits the maintenance of a relatively high temperature in the conversion or expansion chamber and prevents the excessive loss of heat by radiation. When carbon accumulation has become excessive in the

expansion chamber, it may be removed through the manholes at the top and bottom of the chamber.

As an illustrative run in the apparatus, 5 Mid-Continent gas oil of approximately 32° Baumé gravity when treated at temperatures ranging from 700° to 900° F., and at a relatively constant pressure of 125 pounds per square inch, a good quality distillate having 10 a gravity of from 49° to 52° Baumé and comprising from 40% to 60% of the charging stock was obtained. These temperatures and pressures are merely illustrative, and may be changed according to the type of oil used, 15 and the condition desired in the apparatus. It is also not the purpose of this illustration to limit the invention to these particular operating conditions as pressures from 50 to 500 pounds may be utilized, while the temperatures may range accordingly.

I claim as my invention:

1. In an apparatus for converting petroleum oil, the combination with means for heating the oil to a conversion temperature, 25 of an expansion chamber comprising inner and outer receptacles wherein the oil is maintained in conversion pools, means for directing the oil from the heating means to the inner receptacle to overflow into the outer receptacle, dephlegmating and condensing means, means for returning the reflux condensate from the dephlegmating means to the expansion chamber for retreatment, and independent means for withdrawing the un- 30 vaporized products from the separate receptacles while maintaining a regulated pressure upon the oil undergoing treatment.

2. A process for converting hydrocarbon oil, consisting in raising the oil to a conversion temperature in a heating zone, in delivering the heated oil to a body of oil within an enlarged expansion zone, in permitting the oil to overflow from said body into a second body of oil in said enlarged expansion zone, 45 in taking off vapors from both of said bodies and in subjecting such vapors to reflux condensation, in returning the reflux condensate

to said second body of oil, in withdrawing the heavy carbon-containing residue from the first mentioned body of oil and in heating 50 the second body of oil while in said expansion zone, and in maintaining a self-generated superatmospheric pressure on the oil undergoing conversion in the process.

3. An apparatus for converting petroleum oil comprising means for heating the oil to a conversion temperature, an expansion chamber comprising inner and outer receptacles wherein the oil accumulates in pools, said inner receptacle being so constructed as to permit oil to overflow therefrom into the outer receptacle, means for directing the oil from the heating means to the inner receptacle to overflow into the outer receptacle, dephlegmating and condensing means, means for delivering the evolved vapors from said expansion chamber to said dephlegmating and condensing means, means for returning reflux condensate separated from the vapors in said dephlegmating means to said outer receptacle, 70 and means for maintaining a regulated pressure upon the oil undergoing treatment in the apparatus.

4. A process for converting hydrocarbon oil, consisting in raising the oil to a conversion temperature in a heating zone, in delivering the heated oil to a body of oil within an enlarged expansion zone, in permitting the oil to overflow from said body into a second body of oil in said enlarged expansion 80 zone, in taking off vapors from both of said bodies and in subjecting such vapors to reflux condensation, in returning the reflux condensate to said second body of oil, in withdrawing the heavy carbon-containing residue 85 from the first mentioned body of oil, in heating the oil and reflux condensate collecting in said second body to effect further conversion thereof while maintained apart from the heavy oil in said first body, and maintaining a self-generated superatmospheric pressure 90 on the oil undergoing conversion in the process.

GUSTAV EGLOFF.
